UNITED STATES PATENT OFFICE

105,927

DESIGN FOR A DRESS

David Rosenthal, New York, N. Y.

Application July 23, 1937, Serial No. 70,593

Term of patent 3½ years

To all whom it may concern:

Be it known that I, David Rosenthal, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The belt portion of the dress is pulled through a central slit opening beneath the tucked portion, as shown.

I claim:

The ornamental design for a dress, substantially as shown, and described.

DAVID ROSENTHAL,
